THE NORRIS PETERS CO., PHOTO-LITHO., WASHINGTON, D. C.

UNITED STATES PATENT OFFICE.

ROBERT M. DYER, OF CHICAGO, ILLINOIS, ASSIGNOR TO AERMOTOR COMPANY, OF SAME PLACE.

PUMP CONNECTION.

SPECIFICATION forming part of Letters Patent No. 678,554, dated July 16, 1901.

Application filed September 2, 1899. Serial No. 729,282. (No model.)

To all whom it may concern:

Be it known that I, ROBERT M. DYER, a citizen of the United States, residing at Chicago, in the county of Cook and State of Illinois, have invented a certain new and useful Improvement in Pump Connections, of which the following is a full, clear, concise, and exact description, reference being had to the accompanying drawings, forming a part of this specification.

My invention relates to a pump connection, my object being to provide a device whereby a pump-rod may be at will connected with either of two independent sources of power—as, for instance, the reciprocating rod of a windmill and the handle or manual lever of a pump.

When pumps are employed in connection with windmills, it is usually desirable to have a manual lever or handle for the pump which can be connected with the pump-rod to operate the pump manually at times when it is not desired to operate the windmill. It has been the usual practice to provide means whereby either the reciprocating rod of the windmill or the pump-handle can be connected with the pump-rod; but these means are usually separate and distinct, and it frequently happens that both the reciprocating rod of the mill and the pump-handle are left connected with the pump at the same time, in which case, due to the difference in stroke of the two means of applying power, some part of the apparatus is broken, the top or head of the pump-barrel being usually the part which gives way and is broken.

In accordance with the present invention I provide a handle which is connected with the connecting devices of the pump-handle and the reciprocating rod in such manner that when the handle is moved into one position one of the two parts through which power is supplied is connected with the pump-rod, while when the handle is moved into the alternative position the other of the two parts is connected with the pump-rod. By this arrangement the connection of the pump-rod with but one of the two operating parts is insured. I preferably mount the operating-handle upon the pump-handle, so that when the mill-rod is connected with the pump-rod

the operating-handle remains at rest relatively to the mill-rod and may be readily grasped to disconnect the mill-rod and to connect the pump-handle.

55

I have illustrated my invention in the accompanying drawings, in which—

Figure 1 is a view in elevation illustrating my invention. Fig. 2 is a detail view of the connecting devices. Fig. 3 is a sectional view on line 3 3, Fig. 2. Fig. 4 is a sectional view on line 4 4, Fig. 2. Fig. 5 is a detailed view of one of the cams. Fig. 6 is a detailed view of one of the locking-pins. Fig. 7 is a view illustrating the bearing of the cam.

65

Like letters refer to like parts in the several figures.

The pump-rod *a*, which passes through the upper end of the pump-barrel *a'*, is adapted to be connected either with the handle *b* or with the reciprocating rod *c*, which is moved alternately up and down through the action of the windmill or other source of mechanical power. To the end of the handle or manual lever *b* is secured a collar *b'*, which surrounds the pump-rod *a*, the end of the handle being pivoted to the collar at *b*². Upon the lower end of the rod *c* is carried a collar *c'*, which surrounds the pump-rod *a*. A pin *b*³ is adapted to move in an opening *b*⁴, which extends transversely through the collar *b'*, and this pin is adapted to pass through a hole *a*² in the pump-rod *a* when it is desired to secure the handle to the pump-rod. The pin *b*³ carries a transverse opening *b*⁵, into which extends the end of a spring-rod *b*⁶, which is provided with a coil *b*⁷ and is secured at the opposite end in a hole provided in the lug *b*⁸, supported upon the collar *b'*. A slot *b*⁹ is provided, within which the end of the spring-rod is adapted to travel as the pin *b*³ is moved back and forth in its bearing. A cam *d* is journaled to rock within a bearing carried upon the sleeve *b'* and is provided with a square hole through which passes the operating-rod *e*, carrying upon the upper end the handle *e'*. The rod *e* passes loosely through the opening in the cam *d*, and the cam is provided with an arc-shaped portion *d'*, which is adapted to bear against the arc-shaped wall *d*² to thus relieve the rod *e* of any strains that would otherwise be imposed thereon.

95

100

The edge of the cam is provided with a groove d^3 , within which the spring-rod b^6 is adapted to rest, and when the handle e' is operated to rock the rod e the cam d is rocked into the position shown in Fig. 4, in which case the locking-pin b^3 is moved outward out of engagement with the pump-rod a and the pump-rod is thus detached from the sleeve b' . When the rod is rocked to a position at right angles, the cam d is moved out of the path of the spring-rod b^6 and the spring-rod moved inward, thereby carrying the locking-pin b^3 inward to engage the hole a^2 in the pump-rod and thereby lock the pump-rod to the handle b .

The sleeve c' , connected with the rod c , operated by the mill, carries a pin c^3 , adapted to move in an opening c^4 , extending transversely through the sleeve c' . A spring-rod c^6 engages an opening in the locking-pin c^3 , whereby the locking-pin may be moved back and forth, and the spring-rod c^6 is provided with a loop c^7 , which imparts resiliency thereto, and the opposite end is secured in a lug c^8 , carried upon the sleeve c' . A cam f , similar to cam d , is mounted in a bearing carried by the sleeve c' and is provided with a square hole through which passes the rod e . The cam f is provided with an arc-shaped portion f' , similar to the part d' of cam d , and this arc-shaped portion is adapted to bear against the arc-shaped wall f^2 to relieve the rod e of any strains. When the rod e occupies the position shown in Fig. 3, the cam is in position to maintain the locking-pin c^3 in engagement with a hole provided through the pump-rod a , thereby locking the pump-rod to the sleeve c' , and consequently to the rod c . When the rod e is rocked by means of the handle e' , the cam engages the spring-rod c^6 and moves the same outward, carrying with it the pin c^3 , and the pump-rod is thus disengaged. The cams d and f are mounted upon the rod e at right angles to each other, so that when the cam d is in position to withdraw its locking-pin the cam f will be in position to insert the locking-pin belonging thereto, and vice versa. The rocking of the rod e into one position thereof serves to connect the pump-rod with one of the operating devices and to disconnect the same from the other. In the present instance the pins b^{10} b^{11} are provided above and below the sleeve b' , whereby the rod e will be carried up and down with the sleeve b' , while the rod e passes freely through the cam carried by the sleeve c' . The rod e may, however, be mounted upon either of the sleeves b' or c' , the rod being free to move through the cam of the other sleeve.

When it is desired to connect the pump-rod with the windmill, the handle e is moved to rock the rod e into the position shown in Figs. 3 and 4, in which case the pin c^3 will be carried into engagement with the hole in the pump-rod, while the pin b^3 will be moved out of engagement with the pump-rod, and the pump-rod will therefore travel up and down

with the rod c and will move freely within the sleeve b' , secured to the handle b . When it is desired to disconnect the pump from the windmill and to place the same in position to be operated by the handle b , the handle e' is moved to rock the rod e to the alternative position, and cam f is thus moved outward and cam d is moved inward, and pin b^3 is thereby moved into engagement with the pump-rod and pin c^3 is moved out of engagement therewith. This transfer of the connection from one of the operating devices to the other may be made as well while the windmill is operating the pump as when the pump is at rest.

Having described my invention, what I claim as new, and desire to secure by Letters Patent, is—

1. The combination with a pump-rod, of a pump-handle and a mill-rod, means for connecting said pump-rod to said pump-handle, and for releasing said mill-rod, and vice versa, and an operating-handle separate from and independent of the pump-handle for actuating said connecting means and carried on said pump-handle and adapted not to partake of the motion of the mill-rod, substantially as described.

2. The combination with a pump-rod, of a pump-handle and a mill-rod, means for connecting said pump-rod to said handle and for releasing said mill-rod, and vice versa, and an operating-handle separate from and independent of the pump-handle for actuating said connecting means and adapted to be maintained in a stationary position while the pump-rod is connected with the mill-rod, substantially as described.

3. The combination with a pump-rod, of a pump-handle and a mill-rod, means for connecting the said pump-rod to said pump-handle and for releasing said mill-rod, and vice versa, and an operating rod or handle parallel to the pump-rod carried upon the pump-handle and guided by the mill-rod and rotating about its longitudinal axis and adapted to actuate said connecting means, substantially as described.

4. The combination with a pump-rod, of a pump-handle and a mill-rod, a pair of pins, one adapted to be inserted to connect the pump-rod and the handle and the other adapted to be inserted to connect the pump-rod and the mill-rod, a rocking rod extending substantially parallel to said pump-rod, a pair of cams carried thereon, and mechanism between each of said cams and the respective pins whereby the rocking rod in one position inserts the pin which connects the pump-rod with the pump-handle and in another position inserts the pin which connects the pump-rod with the mill-rod, substantially as described.

5. The combination with a pump-rod, of a pump-handle, the operating-rod of a windmill, a pair of locking-pins one for locking the pump-rod to the pump-handle and the other for locking the pump-rod to the reciprocating rod, a yieldingly-pressed rod or lever

for each of said locking-pins for moving the same into the locking position, a cam for each of said locking-pins for moving the same out of the operative position, and a single operating-handle in addition to the elements above enumerated connected with both of said cams whereby one of the locking-pins may be inserted while the other is withdrawn, substantially as described.

6. The combination with a pump-rod, of a pump-handle and the reciprocating rod of a windmill, a pair of locking-pins for connecting the pump-handle and the reciprocating rod respectively to the pump-rod, a yieldingly-pressed lever provided in connection with each locking-pin for moving the same into the locking position, a pair of cams one engaging each of said spring-pressed levers for withdrawing the locking-pins, and a single operating rod or part upon which said cams are mounted to rotate therewith while partaking of a relative movement along the axis of the rod, substantially as described.

7. The combination with the pump-rod *a* of the pump-handle *b* and the reciprocating rod *c*, the sleeves *b'* *c'* and the locking-pins *b³* *c³*, the yieldingly-pressed levers *b⁶* *c⁶* for inserting the locking-pins, the cams *d* and *f* placed at an angle for withdrawing the locking-pins, and the operating-rod *e* for rotating the cams, substantially as described.

8. The combination with a pump-rod, of a

pump-handle and a mill-rod adapted to be separately connected with said pump-rod, a pin for connecting said pump-rod with said pump-handle, a second pin for connecting said pump-rod to said mill-rod, a pair of cams for controlling said pins and an operating rod or handle rotating about its longitudinal axis and adapted to actuate said cams to connect 40 the pump-rod with the pump-handle and release the mill-rod, and vice versa, substantially as described.

9. The combination with a pump-rod, of a pump-handle and a mill-rod adapted to be 45 separately connected with said pump-rod, a pin for connecting said pump-rod with said pump-handle, a pin for connecting said pump-rod with said mill-rod, a pair of cams for controlling said pins, and an operating rod or 50 handle rotating about its longitudinal axis and carried upon said pump-handle and adapted to move relatively to said mill-rod and adapted in one position to connect said pump-rod with the pump-handle and in another position to connect said pump-rod with the mill-rod, substantially as described.

In witness whereof I have hereunto subscribed my name in the presence of two witnesses.
